ARTIST'S WORKING PAPER

Joseph F. Murphy, West Roxbury, Mass.

No Drawing. Application December 27, 1939,
Serial No. 311,156

4 Claims. (Cl. 41—17)

My invention relates to the art of printing and consists in a novel artists' working layout paper and method for producing it.

In the preparation of advertisements for printing it often happens that the artist desires shaded backgrounds ranging from black to light gray. To obtain a background other than black, the following method has been heretofore employed. The artist first paints a black patch on cardboard, the patch having the area of the desired background. Lettering or designs are then superposed or stripped in on the black background on the cardboard. Subsequently a sheet of transparent material having a fine screen on its outer surface is placed over the background and taped down along its edges to the cardboard. This screened film is known in the trade as "Ben Day" film and is supplied in various shades. The "Ben Day" film when placed over the black patch on the cardboard produces a gray which is light or dark according to the shade of "Ben Day" film used. The layout thus formed is photographed to produce a negative from which a metal plate may be made for letter press or photograph offset printing.

The foregoing method of composing a layout and making a half tone negative is complicated, slow and expensive, and it is one important object of my invention to eliminate the necessity for painting a background upon the paper from which the layout is made.

A further object of my invention is to render it unnecessary for the artist to use a half tone or "Ben Day" film screen in making a photographic negative of the layout.

Briefly speaking, my invention consists in a process of preparing drawing paper by means of which an artist engaged in making up an illustration or advertisement is provided from the start with a shaded and screened background, the background being printed in the form of fine reticulated lines on paper which can be drawn upon, painted, cleaned, or erased. The paper produced by the practice of my novel process is also included within the scope of my invention.

To produce the paper of my invention, an artist first paints in water color upon a sheet of cardboard or other fairly stiff material the proper shade of gray or black which is desired. The shading can be of uniform color or may contain zones of different shades, sharply demarcated or gradually blending into one another. Furthermore the artist may paint background designs, such as stars, circles, etc., in contrasting shades of gray or black. When the artist has com-

pleted his work, the shaded sheet is photographed through a half tone screen so that the negative thus produced contains both the shading and the screening. A 60 mesh screen may be used where the product is to be employed in newspaper work. Finer screens are used for magazines and more expensive publications.

From the screened negative it is possible to make positives on sensitized drawing paper. These positives then become articles of commerce and can be advantageously employed in making up advertisements. The screening step results in a positive having a plurality of fine, reticulated black lines, the interstices being white, or neutral, according to the color of the paper upon which the print is made. The lines on the prints are, of course, in sufficiently close proximity to one another to give the shaded half-tone effect desired.

A cheaper and more practical method is to make a metal plate from the screened negative and to print positives from the metal plate on drawing paper which has, in this case, not been sensitized. The sheets of drawing paper so printed contain the screened shading.

The use of the artist's working paper produced by my novel process renders the making of an advertisement much cheaper than it has been heretofore, in view of the fact that the necessity for making a half tone negative of the layout is eliminated. The person making up the advertisements can work directly on my novel paper and either draw the lettering or design which is to appear on the background or can strip in type which is pasted down on the shaded and screened background of my paper.

Although many different kinds of paper may be used, I prefer to use artist's paper of high quality, such as No. 1 gloss paper upon which to photograph or print the screened shade. The artist's layout paper thus produced will lie flat, can be drawn or painted on, and permits cleaning and erasing without smudging or otherwise damaging the paper or the screened background.

Having thus described my invention what I claim as new and desire to secure by Letters Patent of the United States is,

1. As an article of commerce, artist's working layout paper in sheet form for drawing upon having one surface thereof provided with reticulated lines sufficiently closely spaced to give a half-tone shading effect on said surface.

2. As an article of commerce, artist's working paper in sheet form for drawing upon having one of its surfaces provided with a half-tone

shading formed of closely spaced reticulated lines.

3. As an article of commerce, artist's working paper in sheet form for drawing upon having one of its surfaces provided with a gray shading composed of black areas substantially uniformly distributed and spaced closely enough to give a half-tone effect.

4. As an article of commerce, a substantially opaque sheet of artist's paper of a grade and quality for being drawn upon with pencil or pen and having one surface thereof provided with reticulated lines sufficiently closely spaced to give a half-tone effect on said surface. 5

JOSEPH F. MURPHY.
